[57] CLAIM

The ornamental design for a tape cassette for a label printer, as shown and described.

DESCRIPTION

FIG. 1 is a top plan view of a tape cassette for a label printer showing our new design;

FIG. 2 is a perspective rear view thereof taken from the bottom, front and left side;

FIG. 3 is a rear elevational view thereof;

FIG. 4 is a right side elevational view thereof with the tape removed for convenience of illustration;

FIG. 5 is a left side elevational view thereof with the tape removed for convenience of illustration; and,

FIG. 6 is a top plan view of a second embodiment of FIG. 1, the difference being that the cover is made of an opaque material, all other views are identical to the first embodiment.
